UNITED STATES PATENT OFFICE

BERT R. PRALL, OF CHICAGO, ILLINOIS, ASSIGNOR TO MONTGOMERY WARD & CO., INCORPORATED, OF CHICAGO, ILLINOIS, A CORPORATION OF ILLINOIS

DESIGN FOR A TIRE CASING

Application filed October 11, 1929. Serial No. 33,007. Term of patent 14 years.

To all whom it may concern:

Be it known that I, BERT R. PRALL, a citizen of the United States, residing at Chicago, in the county of Cook and State of Illinois, have invented a new, original, and ornamental Design for Tire Casing, of which the following is a specification, reference being had to the accompanying drawing, forming a part hereof.

In the drawing:

Fig. 1 is a top plan view of a portion of a tire casing embodying the present design;

Fig. 2 is a fragmentary side elevation of the same; and

Fig. 3 is a cross sectional view on the line 3—3, Fig. 1.

I claim:

The ornamental design for a tire casing, substantially as shown.

BERT R. PRALL.
